UNITED STATES PATENT OFFICE.

LESLIE E. WRIGHT, OF MORGAN CITY, LOUISIANA.

FAUCET-CASING.

1,084,996.

Specification of Letters Patent. Patented Jan. 20, 1914.

Application filed March 28, 1913. Serial No. 757,464.

To all whom it may concern:

Be it known that I, LESLIE EDWIN WRIGHT, a citizen of the United States, residing at Morgan City, in the parish of St. Mary and State of Louisiana, have invented new and useful Improvements in Faucet-Casings, of which the following is a specification.

The invention relates to faucet casings, and has for its primary object to provide a device of this character wherein the faucet will be protected so as to prevent tampering therewith by a malicious person or persons.

Another object of the invention is the provision of a casing of this character in which a faucet may be concealed so that the turning valve thereof cannot be manipulated unless the said casing has been opened; thus obviating tampering therewith by persons other than the rightful person, the casing being readily and easily applied to or removed from the faucet.

A further object of the invention is the provision of a casing of this character which is extremely simple in construction and inexpensive in manufacture.

With these and other objects in view, the invention consists in the construction, combination and arrangement of parts as will be hereinafter fully described, illustrated in the accompanying drawing, and pointed out in the claim hereunto appended.

In the drawings:—Figure 1 is a side elevation of a faucet showing a casing constructed in accordance with the invention applied thereto. Fig. 2 is an end elevation. Fig. 3 is a similar view looking toward the opposite end. Fig. 4 is a sectional view on the line 4—4 of Fig. 1.

Similar reference characters indicate corresponding parts throughout the several views in the drawing.

Referring to the drawings by numerals, 5 designates a faucet having a discharge mouth or nozzle 6 and a turning valve stem 7 which is mounted therein in the usual well-known manner and is adapted to control the fluid supply through the faucet as usual, the body of the faucet 5 being formed spaced from its rear end with an abutment shoulder 8 which co-operates with the casing presently described.

The casing comprises a cylindrical body including upper and lower sections 9 and 10 respectively which are of complementary shape with respect to each other, and each

has formed at its outer end a semi-circular shaped end wall or cheek 11, while its opposite inner end is formed with an inturned flange 12 which encircles one-half of the faucet 5 and is adapted to abut against the shoulder 8 thereon, the upper section 9 being connected to the lower section 10 through the medium of a pintle hinge 13 which permits the opening of the upper section 9 for the applying of the casing on a faucet or the removal of the said casing therefrom. Suitably secured to or integrally formed with the lower section 10 is a depending spout 14 which receives the mouth or discharge nipple 6 of the faucet, it being seen that when the casing is applied the sections 9 and 10 thereof will embrace the body 5 of the faucet as shown in Fig. 1, and when the sections are closed the turning valve stem 7 will be located within the casing so as to not be accessible until the casing has been opened or removed from the faucet. Thus it will be noted that the faucet cannot be tampered with for the turning on or off of the fluid supply delivered thereto.

Mounted in the lower section 10 of the casing at one side thereof is a staple forming a keeper 15 which is engaged by a latch or hasp member 16 hinged at 17 to one side of the upper section 9, and when the latch or hasp 16 is engaged with the staple 15 an ordinary lock can be applied to the latter for fastening the sections 9 and 10 closed so as to conceal the faucet and obviate tampering with the same by a malicious person. The hasp member 16 has riveted or otherwise fixed therein, on opposite sides of the opening contained therein for receiving the keeper 15, eye members 18, one of which is slightly larger than the other, and through these eye members is passed a holding pin 19 which is formed at one end with a head 20 and at its opposite end is provided an enlargement 21 which engages in the larger eye member 18 while the head 20 limits the movement of the pin in one direction by contacting with the other or smaller eye member 18, the pin being designed to work against the keeper 15 when the hasp member 16 is engaged therewith so as to prevent the lowering of the bottom section 10 with respect to the top section 9, that is to say, in other words, the two sections 9 and 10 when closed will be held in such position so that the edges adjacent to each other will contact

and thereby avoid the separation or opening of the sections when closed as will be clearly apparent.

From the foregoing, it is thought that the construction and manner of operation of the device will be clearly understood, and therefore a more extended explanation has been omitted.

What is claimed is:—

- 10 The combination with a valved faucet, of a casing therefor comprising a two-part hollow body, a hinge connecting the two parts of the body together, a hasp carried by one of the parts, a staple carried by the
- 15 other part and engaged by the hasp, eyes formed on the hasp, a retaining pin passed

through the eyes to lie beneath the staple and adapted to engage with a lock when connected to the staple to hold the two parts of the body firmly together, said casing being adapted to receive the faucet and its valve for inclosing the same, and a depending nipple formed on one of the parts and surrounding the discharge spout of the faucet.
